UNITED STATES PATENT OFFICE.

HARRY M. SMITH, OF CHICAGO, ILLINOIS; ASSIGNOR TO LYON & HEALY, OF CHICAGO, ILLINOIS, A CORPORATION OF ILLINOIS.

VALVE FOR PIANO OR ORGAN PLAYERS.

No. 878,096.

Specification of Letters Patent.

Patented Feb. 4, 1908.

Application filed November 3, 1906. Serial No. 341,959.

To all whom it may concern:

Be it known that I, HARRY M. SMITH, a citizen of the United States of America, and resident of Chicago, Cook county, Illinois, have invented a certain new and useful Improvement in Valves for Piano or Organ Players, of which the following is a specification.

This invention relates to improvements in secondary valves intended for use in mechanical musical instruments, though in some of its features it may be of more general application, and has for its object the provision of a valve which shall be efficient and durable in operation and economical in the cost of manufacture. The kind of valve which I prefer to use for this purpose is of the double-acting type or one having two active outer valve-faces which are adapted to open and close upper and lower valve-ports in seats coöoperating with said faces. It is also desirable to have the valve so constructed that its parts may be easily assembled in place and readily removed for the purpose of repair or substitution.

To the foregoing and other useful ends, my invention consists in matters hereinafter set forth and claimed.

In the accompanying drawings, Figure 1 is a sectional view showing a piano or organ player provided with the valve arrangement embodying the principle of my invention. Fig. 2 is an enlarged detail section of the said valve arrangement. Fig. 3 is a plan view of one of the valve-seats.

It will be readily understood that the general construction of the piano or organ player may be of any suitable known or approved character. As shown, it comprises the usual tracker-board A, the music-rolls B and B¹, and a motor C; it being understood that the said rolls carry the usual strip of perforated music. Other familiar elements of an instrument of this character consist of the fingers D and the pneumatics E, together with the treadle-operated bellows or exhaust apparatus F. The primary valves within the casing G may be of any suitable or desired character; but the secondary valves within the casing H are, as previously explained, preferably constructed in accordance with my invention.

In Fig. 1 a portion of the casing H is broken away for the purpose of showing one of the secondary valves I, and in Fig. 2 this

valve is shown on an enlarged scale. As illustrated, the construction preferably comprises a valve-board i provided with a vertical chamber or passage i¹, desirably open at top and bottom, and communicating at one side with the longitudinal passage i². At its upper end, the valve-chamber i¹ is provided with a valve i³, and at its lower end with a similar valve-seat i⁴. As shown, each valve-seat consists of a flat disk apertured at its center and provided on its inner surface with an annular offset or seat adapting it to partially fit within the chamber i¹. For example, as shown in Fig. 3, the valve-seat i³ consists of a disk provided centrally with the air passage i⁵ and with a bearing i⁶ for a valve-stem, and on its under side the said valve-seat i³ is provided with an annular and marginal offset or seat i⁷. In this way, said valve-seat is adapted to partially fit within the open upper end of the valve-chamber i¹, being provided with a marginal flange, so to speak, which rests upon the upper surface of the valve board i. The valve-seat i⁴ is of similar formation, with the exception that its central opening or bearing i⁸ for the valve-stem is somewhat larger than the opening i⁶. The said valve-stem i⁹ is preferably provided with a lower enlarged portion i¹⁰, which latter in effect provides a shoulder i¹¹ and a foot i¹². The upper and lower valve-disks i¹³ and i¹⁴ are mounted upon the smaller diameter of the valve-stem i⁹, and are separated by any suitable means such (for example) as a ball i¹⁵, the two disks and separating ball or member being strung upon the valve-stem in the manner shown in Fig. 2. Preferably, the disks and said ball or separating member are adapted to fit tightly upon the said stem and to remain in their proper places thereon when once properly adjusted. As shown, the two valve-disks, separated by the ball or separating member, are crowded down upon the shoulder i¹¹. Both valve-seats are provided with smooth inner surfaces, being made of any suitable or desired material. In this way, the lower surface of the disk i¹⁴ is adapted to normally rest upon the smooth inner or upper surface of the valve-seat i⁴, and to thereby close the passage with which the latter is provided. The outer or upper surface of the disk i¹³ is adapted to bear upon the smooth inner or lower surface of the valve-seat i³—that is to say, when the valve-disks and valve-stem as

a whole are raised from their normal position. As shown, a palate i^{16} , or other suitable pneumatic device, communicating with a wind-way i^{17} , is provided as a means for raising and 5 lowering the rigid or operative member composed of the two valve-disks and the valve-stem, the said palate or other pneumatic device being adapted to engage the foot or enlargement i^{12} carried by the lower end of the 10 valve-stem.

The two valve-seats i^3 and i^4 can be made of any suitable material; but as a matter of further and specific improvement, I find that celluloid gives very good results. Each 15 valve-seat constitutes both a seat for one valve-disk and a bearing for the valve-stem. With the provision of the shoulder i^{11} , the valve-disks cannot slip down upon the valve-stem, and cannot become disarranged or 20 thrown out of adjustment relative to each other and relative to the valve-seats. The construction, although comparatively simple, is effective in securing a certain and positive opening and closing action, and in addition, 25 no screw-thread adjustments are necessary. Furthermore, the parts are easily assembled or separated from each other.

What I claim as my invention is:

1. A piano or organ player comprising a 30 valve-chamber, apertured valve-seats fitted within the upper and lower ends of said chamber, a valve-stem provided with a shoulder and adapted to slide up and down in the bearing afforded by said valve-seats, a 35 couple of valve-disks fitted upon said stem, and a separating member fitted upon said stem and separating the two valve-disks, said valve-disks and their separating member being so adjusted as to rest upon said shoulder.

2. A piano or organ player comprising a 40 valve-chamber, apertured valve-seats applied to the upper and lower ends of said chamber, a shouldered valve-stem extending through both of said valve-seats, and a couple of separated valve-disks fitted upon 45 the said stem and held against the shoulder thereon, said disks being adapted to play between the said valve-seats.

3. A piano or organ player comprising a tracker-board, and perforated music, fingers 50 actuated by power pneumatics, exhaust apparatus, a horizontally disposed valve-board provided with a valve-chamber, valve-seats consisting of flat apertured disks fitted within the upper and lower ends of said chamber, 55 a shouldered valve-stem extending through both of said valve-seats, a couple of separated valve-disks mounted upon said stem and resting upon the shoulder thereof, each valve-seat having an integral portion serving 60 as a bearing for the valve-stem, and a pneumatically-actuated diaphragm arranged to engage the lower end of said valve-stem.

4. A piano or organ player comprising a 65 valve chamber, apertured valve-seats fitting within the upper and lower ends of said chamber, a valve-stem adapted to slide up and down in the bearing afforded by said valve-seats, a couple of valve disks fitted upon 70 said stem, and a separating member fitting upon said stem and separating said valve disks.

Signed by me at Chicago, Illinois, this 28th day of June, 1906.

HARRY M. SMITH.
